UNITED STATES PATENT OFFICE.

MARY E. LA RUE, OF RICHMOND, KENTUCKY.

CURTAIN-RING.

No. 885,932.

Specification of Letters Patent.

Patented April 28, 1908.

Application filed January 18, 1908. Serial No. 411,447.

To all whom it may concern:

Be it known that I, MARY E. LA RUE, a citizen of the United States, residing at Richmond, in the county of Madison and State of Kentucky, have invented a new and useful Curtain-Ring, of which the following is a specification.

This invention relates to curtain rings for suspending lace and other curtains from a pole; and has for its object to provide a ring made from a single piece of metal fashioned in such shape as to form, not only a ring to engage a pole, but also a depending hook or pin from which the curtain is suspended and a keeper for said hook to retain the curtain in place thereon.

With this and other objects in view, the invention comprises the construction and arrangement of parts hereinafter described and claimed reference being had to the accompanying drawing forming a part of this specification, in which

Figure 1 is a perspective view of a short section of curtain pole, two of the improved curtain rings and part of a curtain suspended therefrom; Fig. 2 is an enlarged side view of the lower portion of the curtain ring illustrating more clearly the construction of the hook or pin and its keeper; Fig. 3 is a detail view looking in the direction of the arrows on line 3—3, and Fig. 4 is a similar view of a modified form of the invention.

Similar numerals of reference are used for the same parts in all the figures.

The numeral 1 indicates a portion of a curtain pole carrying two curtain rings 2 and from hook shaped spring pins 3 thereon are suspended a curtain 4, a part only of the latter being shown. Each curtain ring with its attached spring pin 3 is made of a single piece of wire bent, twisted and folded until it assumes the shape represented in Figs. 1, 2 and 3. From an inspection of these figures it will be observed that a length of wire is first bent upon itself at or near the center of its length and the two strands thus formed twisted together evenly from the folded end where an eye 5 is formed nearly to the extreme ends 6 and 7 of the strands. The eye 5 and the two loose ends of the strands are brought together, to form the curtain ring 2, the eye 5 and the loose ends 6 and 7 of the wire being fastened together as shown in the drawing and now to be described.

After forming the ring 2, one end, as 6, is threaded through the eye 5 and the latter

drawn as close as possible to the last crossing of the wire ends 6 and 7, and then bent downwardly. The other wire end 7 is also bent downwardly outside the eye 5 a suitable distance and then turned in an upward direction to form the spring pin 3. The end of the strand 6 is given a complete turn 8 about the descending arm of the spring pin 3 and then extends in a horizontal direction to and around the pointed end 9 of the pin and back again, forming the keeper 10 for the pin point.

The wire for the combined curtain ring and pin should be made of spring metal such as steel, brass, phosphor bronze etc., and instead of twisting the strands through their entire length they may remain parallel to each other as represented in Fig. 4, except at the ends where two or three turns 11 and 12 are made 70 the turns 11 to form the eye 5 and the other turns 12 to hold the ends 6 and 7 of the strands of wire together. The spring pin 3 and its keeper 10 lie preferably in a plane parallel to the ring 2, but may if desired be placed at 80 right angles thereto.

Constructed as described, each curtain ring will have an integral curtain support and spring pin forming a part thereof, so that hanging curtains will be an easy matter and 85 free from the annoyance of hunting for pins at most inopportune times. The rings are light, strong and ornamental without being obtrusive. The fastening between the loop and the free ends of the strands is simple, 90 strong and easily made and cannot separate without some part of the connection breaking.

What is claimed is:

1. As an article of manufacture a curtain ring, a curtain pin and a keeper for said pin 95 made of a single piece of spring wire doubled upon itself the two strands thus formed being bent into a ring and firmly connected at their ends by looping one of the wire ends into the eye formed by doubling the wire, one of said wire ends being bent to form a spring hook and the other a keeper for the same.

2. As an article of manufacture a curtain ring formed of a single piece of wire doubled upon itself and the doubled portion bent to form the ring, one end of said wire being bent into a spring pin, and the other end after passing through the loop formed by doubling the wire, being bent around the first named 105 wire near said loop and then around the pin 110 to form a keeper therefor.

3. As an article of manufacture a curtain ring formed of a single piece of wire doubled upon itself and twisted throughout its length except for a short distance at the ends of the 5 wire, and then bent to form the ring, one of said free ends being fashioned into a spring pin with an upwardly extending pointed end, and the other free end after first passing through the doubled end of the ring being 10 bent around the base of the spring pin for a

full turn and then formed into a keeper for the end of said pin.

In testimony that I claim the foregoing as my own, I have hereto affixed my signature in the presence of two witnesses.

MARY E. LA RUE.
